UNITED STATES PATENT OFFICE.

GEORGE H. GUINN, OF CINCINNATI, OHIO, ASSIGNOR TO CHARLES S. GUINN, OF WAYNESBURG, KENTUCKY.

SWITCH-LOCK.

1,176,051.

Specification of Letters Patent. Patented Mar. 21, 1916.

Application filed March 3, 1915. Serial No. 11,685.

To all whom it may concern:

Be it known that I, GEORGE H. GUINN, a citizen of the United States, and a resident of the city of Cincinnati, in the county 5 of Hamilton and State of Ohio, have invented certain new and useful Improvements in Switch-Locks, of which the following is a full, clear, and exact description, reference being had to the accompanying 10 drawings, forming part of this specification.

My invention relates to locking devices for street railway switches in particular, although it may be applied to general railroad work as well. In locks of this nature, 15 the effort is to provide a means for insuring a positive complete throw of a switch, and for so locking the switch tongue after the throw that it will require a positive operation to throw it back again.

20 It is the object of my invention to provide a locking device—operated from the switch tongue itself so as to provide for cars coming both ways on a single track, and locked by toothed disks,—which is completely inclosed in a weather and dirtproof 25 box of convenient size, and capable of being packed with fluid grease or the like. This I accomplish by that certain construction and arrangement of parts to be hereinafter 30 more specifically pointed out and claimed wherein a rod from the switch is passed through stuffing boxes into the lock casing, and throws the locking disks referred to by means of an eccentric stud, as will be de- 35 scribed.

In the drawings, Figure 1 is a perspective view of the switch and lock. Fig. 2 is a longitudinal section of the lock. Fig. 3 is a vertical section of the lock taken along the 40 axial line of the switch rod, which for clearness is shown in elevation. Fig. 4 is a perspective view of the sliding block. Fig. 5 is a perspective view of the slideway for the block.

45 The switch shown in the drawings is the ordinary street railway switch, having the switch tongue 1, which is to be thrown by the inserting of a switch iron, in the space between the side of the tongue and one of 50 the rail members 2, 2, of the switch. To the web of one of the rails is secured a box 3, preferably of iron, which has large bolts 4, 4, which pass through the rail for so mounting the box. A rod 5 is secured to the switch

tongue and is passed through a hole 6 in 55 the rail to which the box is mounted, and enters the box near its upper left hand corner through a stuffing box 7. A guide rod 8 extends out from the adjacent front corner of the box, through another stuffing box 60 9, and a cap 10 is fitted over the boss 11 in the box that the stuffing box is mounted in. These two rods are the only members of the lock that pass from the outside into the box, and from the description above it is plain 65 that stuffing boxes completely protect their entrance. The top 12 of the box is bolted down by means of countersunk bolts 13, 13, and the box may be filled with oil or grease, that will preserve the lock in perfect condition after the severest flood or freezing test. 70

The structure of the lock is as follows. A framework comprising end plates 14 and 15 and connected by rods 16 is set into the box, and suitably secured in a sidewise position, and resting on lugs 17, 17, at four points on the bottom of the box. Secured to the forward end piece 14 is a fixed toothed disk 18, which has a central aperture in which is journaled the tubular member 19. 80 A disk 20, having an eccentric stud 21 on its outer face, is mounted on a shaft 22, which is fixedly mounted in the outer end of the tubular member 19. A rod 23 is mounted on the other end piece 15 and extends 85 up into the inner end of the tubular member, said tubular member being adapted to slide up and down on said rod.

A toothed disk 24 is pinned at 25 to the tubular member 19 and a spring 38 secured 90 to the end piece 15 bears with its other end against the collar portion of said toothed disk 24. The eccentric pin 21 is to be actuated by the rod 5 connected to the switch tongue, as described, and this movement will 95 turn the disk 20, the tubular member 19 and force the toothed disk mounted on the said member downwardly against its spring pressure before it can be free from mesh with the fixed toothed disk. A proper positioning of the eccentric stud and proper sized teeth on the disks, is desired so that a throwing of the switch tongue from one side of the switch to the other will result in a moving of the two toothed disks with relation to 100 each other just the distance of one tooth. A partial throwing of the switch tongue will then bring the apices of opposing disk

teeth adjacent to each other and the spring pressure will then throw the switch arm over the rest of the distance, without further work on the part of the operator of the switch. The springs will be strong enough to prevent any accidental jarring from causing the switch to split and the switch will be locked, as the term is employed in this art. The rod running from the switch tongue to the locking device has a straight line motion as it must pass through a stuffing box as described, and accordingly means are provided to transform straight into circular motion by means of the connection of said rod with the eccentric stud heretofore mentioned. The guide rod which, as described, has a mounting at the opposite side of the box from the rod to the switch tongue, is secured to the latter rod and the two form a suitable connection for the eccentric stud, for the purpose mentioned. The ends 27 of the two rods are flattened out, and over the top and bottom of the flattened portions are mounted plates 28, 28, said plates being connected together by means of pins or bolts 29 that pass through the ends of the rods. A block 30, of a size to slide in the space between the flattened rod ends and the top and bottom connecting and spacing plates 30 now described, is provided, having shoulders 31 at each side to bear against the inner sides of the said flattened portions. This block is pierced with a hole of the proper size to fit the eccentric stud 21, and when 35 the parts now detailed are assembled and the rod from the switch actuated, the block will slide up and down to take up the motion necessary to transform the straight into the circular thrust desired, and the stud will be 40 free to rotate in the block, and to slide in the block so as to allow the disk to ride in with the locking disk and tubular member.

When a car having flanged wheels, as customary, rides over the switch coming from 45 the branching tracks onto the single track of the switch the tongue will be forced over by the flange of the wheels. Otherwise the operator of a car must insert his iron in the switch and positively throw the tongue 50 over.

The device is built around a simple toothed disk lock, and its chief advantage lies in the fact that it is absolutely protected from becoming clogged with mud or ice. 55 There have been some devices working on a toothed disk principle in the art, but since it is a requisite for such a structure to be securely protected from weather and street

conditions, there has not been much success as a result of their use.

There are many modifications of my device which the mechanic skilled in the art could make to adapt the protected ratchet device for other railroad work, where other means of turning the switches are employed, 65 such as levers and the like. It would be practical, for example, to adapt some means of working a switch by actuating the guide rod from a switch stand, all of which needs 70 no description.

There are also many modifications of structure in the device itself such as, for example, in the method of transmission from the switch rod to the eccentric stud of the device. These, however, are considered to 75 be developments which it is only necessary to mention to avoid implied limitations in the claims that follow, to specific structure where the same is not directly mentioned in the said claims.

Having thus described my invention, what I claim as new and desire to secure by Letters Patent, is:—

1. In a device of the character described, in combination with a switch movable member, a rod connected thereto, an inclosed chamber forming member, an aperture in said chamber member for the rod, a stuffing box therefor, a fixed toothed member in said chamber, a rotatable toothed member 80 spring pressed into connection therewith and sliding connection between said rod and the movable rotatable member, for the purpose described.

2. In combination with a movable switch member, an inclosed chamber forming member, apertures at two sides of said chamber member, a rod passing through each aperture, stuffing boxes for said apertures, one of said rods connected to the movable switch member, a toothed disk lock, and means whereby said rod engages said lock.

3. In combination with a movable switch member, an inclosed chamber forming member, apertures at two sides of said chamber member, a rod passing through each aperture, stuffing boxes for said apertures, one of said rods connected to the movable switch member, a rotatable toothed disk lock, and means whereby said rod slidably engages 110 said lock.

GEORGE H. GUINN.
